UNITED STATES PATENT OFFICE.

JOHN H. LINDSAY, OF NEW YORK, N. Y., ASSIGNOR OF ONE-HALF TO
FRANK DOBSON, OF NEW YORK, N. Y.

RADIATOR AND COIL.

No. 807,390.

Specification of Letters Patent.

Patented Dec. 12, 1905.

Application filed March 19, 1904. Serial No. 199,047.

To all whom it may concern:

Be it known that I, JOHN H. LINDSAY, a citizen of the United States, residing in the borough of Brooklyn, city of New York, county 5 of Kings, State of New York, have invented a certain new and useful Improvement in Radiators and Coils, of which the following is a specification.

The present invention relates to improvements in radiators or coils and means for attaching shields thereto, and has for its object to simplify the construction of the attaching means for the shield and reduce the cost thereof.

15 The invention also has for its object to improve the effect of the shield by using a plurality of shields instead of a single one.

I accomplish these objects by the device illustrated in the accompanying drawings, in 20 which—

Figure 1 is a top view of the radiator, showing a shield partly in position. Fig. 2 is a front view; Fig. 3, an end view of the same; Fig. 4, an enlarged view in section through 25 a portion of a radiator-section, showing in detail the manner of attaching a single shield. Fig. 5 is a similar view showing two shields in place.

In all of the several views like parts are 30 designated by the same reference-numerals.

In carrying out my invention I provide certain of the radiator-sections 1 with integral lugs 2. These lugs are preferably formed near the top and bottom of a section and on 35 both of the outside faces thereof, as is shown in Fig. 3. For simplicity I prefer to form the lugs on those sections which carry the feet 3, as thereby about the proper proportion of lugs to each radiator will be formed;

40 but this is not essential. The shield 4 may be formed of sheet metal, preferably of a single piece of galvanized iron, and is secured to the radiator by means of the lugs 2. Separating the lugs and the shield and resting on the 45 outer face of each lug is an extension-collar 5, preferably formed of cast-iron. The extension-collar has a hollow center, through which passes a bolt 6, the bolt also passing

through a hole 7 in the shield and a threaded opening or tap 8 in the lug. The bolt is preferably a machine-bolt, and its head rests upon a washer 9, if such washer is desired. As many bolts as there are lugs are preferably used, in Fig. 2 there being six such bolts illustrated on one side of the radiator, this being 55 sufficient for a radiator composed of fifteen sections. For a radiator composed of a greater or lesser number of sections more bolts or less bolts will be used, as necessary.

In Fig. 5 I show two shields upon the same 60 side of the radiator. The inner shield 10 is secured by the same securing-bolt as the outer shield 4; but in lieu of a single collar 5 two collars 11 and 12 are employed. By this construction as many shields as desired may be 65 used, the number of collars being increased and the length of the bolts being governed accordingly.

The openings 7 in the shield are preferably made with a punch, which is a ready means 70 of forming the openings in fitting the shield to the radiator. When so punched, each hole will have a bur 13 on the inner surface. Unless means be provided to accommodate this bur it will prevent the desired connection between 75 the shield and the extension-collar. To permit such a close connection, the collar is counterbored at 14, the counterbore being sufficiently large to take all of the bur.

It is to be understood that the shield may 80 be attached to either or both sides of the radiator, as desired.

The broad invention disclosed herein is not claimed in this application, but in an application for Letters Patent filed by me on the 85 20th day of November, 1905, Serial No. 288,160.

Having thus described my invention, what I claim as new, and desire to secure by Letters Patent, is—

1. In combination with a radiator having threaded lugs cast on the outside thereof, of a sheet-metal shield having punched perforations therein, counterbored spacing-collars between the shield and lugs, and screws for 95 rigidly securing the shield to the lugs, the

said screws passing through the collars, and the bur punched on the shield occupying the counterbore of the spacing-collar.

2. In combination with a radiator having 5 threaded lugs cast on the outside thereof, of a plurality of sheet-metal shields having punched perforations therein, counterbored spacing-collars between the shields, and screws for rigidly securing the shields to the lugs,

the said screws passing through the collars, and the bur punched on a shield occupying the counterbore of a spacing-collar.

This specification signed and witnessed this 17th day of March, 1904.

JOHN H. LINDSAY.
